UNITED STATES PATENT OFFICE.

JOHN W. BROWN, OF COLUMBUS, OHIO, ASSIGNOR TO THE JOHN W. BROWN MANUFACTURING COMPANY, OF COLUMBUS, OHIO, A CORPORATION OF OHIO.

VEHICLE-LAMP.

1,359,323.

Specification of Letters Patent. Patented Nov. 16, 1920.

Application filed September 27, 1919. Serial No. 326,788.

To all whom it may concern:

Be it known that I, JOHN W. BROWN, a citizen of the United States, residing at Columbus, in the county of Franklin and State of Ohio, have invented certain new and useful Improvements in Vehicle-Lamps, of which the following is a specification.

This invention relates broadly to vehicle lamps, and has particular reference to lamps of the type employed as head lights for automobiles.

The object of the present invention resides essentially in the provision of novel means for effecting the securing of the door of the lamp in firmly united relationship with the body or casing thereof and to perform this result in such manner that the reflector of the lamp will be securely held within said casing and prevented from vibrating or chattering therein.

Another object of the invention resides in providing novel interlocking devices between the door of the lamp and said casing, said devices permitting the door to be connected with the casing by mere longitudinal movement of said door and without involving the necessity of rotating the latter to effect its fastening.

Other objects of the invention reside in a lamp which may be economically produced, of few and simple parts and wherein the various elements of the lamp when assembled are firmly and securely held in their respective positions and in the provision of positive and reliable means for retaining the elements in their operative positions.

With these and other objects in view, as will appear as the description proceeds, the invention accordingly consists in the novel features of construction, combinations of elements, and arrangement of parts herein-after to be fully described and to have the scope thereof pointed out in the appended claims.

In the accompanying drawing, forming a part of this specification, and in which similar characters of reference denote like and corresponding parts:

Figure 1 is a vertical longitudinal sectional view taken through a vehicle lamp

constructed in accordance with the principles of the present invention,

Fig. 2 is a horizontal sectional view, disclosing more particularly the interlocking elements between the casing of the lamp and the door thereof,

Fig. 3 is a fragmentary perspective view of a lamp door and illustrating its locking projection,

Fig. 4 is a fragmentary detail view, showing a portion of the casing and the actuating knob.

Referring more particularly to the details of the present invention, use is made of a vehicle lamp 1. This lamp, in its preferred form, consists of a parabolical shaped casing 2 preferably formed from thin sheet metal and having an outer and open end. In the present instance the rim of the casing 2 is inwardly bent so as to provide an annular 70 flange 3, the plane of which being located substantially at right angles to the longitudinal axis of the casing. It is stated that the flange 3 is of annular formation, however, this formation is optional, as it will 75 appear as the description proceeds that the flange 3 could be in the nature of a series of projections extending inwardly from the casing instead of the annular contiguous formation shown and described. Therefore, 80 by the term flange I mean any inwardly extending projection or formation either integral or otherwise upon the rim of the casing 2. Situated within the casing 2 is the usual parabolical reflector 4. In this instance the reflector is formed to comprise a peripheral flange 5, which is arranged to seat directly upon the flange 3. The flange 5 is provided with a grooved portion 6 in which a circular gasket 7 is seated. The 85 portion 6 is preferably located on a plane beyond or outside of the flange 5, in order that the gasket 7 will be appreciably spaced from the flange 5. If desired, said flange 5 may be provided with circumferential recesses 8, which are of sufficient area to receive a plurality of tongues 9 which are carried upon the casing flange 3. Manifestly, by seating the reflector upon the flange 3 and then by rotating the same, the portions 100

of the flange 5 contiguous to the recesses 8 may be inserted between the outer ends of the tongues 9 and the flange 3. In this manner, the tongues 9 will consist in serving 5 to retain the reflector in secured relationship with the casing. It will of course be understood that the casing 2 and the reflector may be provided with any desired number of illuminating lamps and their associated wiring connections.

In connection with the casing and reflector, I employ a closure or door 10. This door consists essentially of a ring shaped body 11 which comprises an annular horizontal wall 12 and a vertical annular wall 13, the wall 12 being disposed so as to overlie and surround the rim portion of the casing 2 and is provided with an inwardly directed bead 14 on its rim. The vertical wall 15 20 is, in turn, provided with a circular opening over which is fitted a transparent panel or lens 15, which is retained in position by providing the inner face of the wall 13 with a plurality of resilient prongs 16, 25 which contact and engage with the periphery of the lens so as to hold the latter in secured relationship with the door. When the parts of the lamp are assembled it will be obvious that the inner face of the lens 15 30 will press upon the gasket 7 and in this manner a seat is provided for the door which will be of a resilient nature and also capable of sealing the interior of the lamp so as to prevent the ingress of dust or other extraneous material, thus serving to preserve the finely polished surface of the reflector.

In order to firmly and positively retain the door 10 in secured relationship in connection with the casing 2 and at the same time to lock the reflector 4 therein, said door 10 in this instance is provided with an inwardly directed and rigidly mounted stud or projection 17, which extends from the horizontal wall 12 of the door and occupies 45 a position substantially parallel with the flanges 3 and 5. To receive the projection 17, the casing 2 has its rim provided with a slot 18 which extends parallel with the longitudinal axis of the lamp. This slot is provided 50 with a widened entrance portion and a restricted inner portion, the widened portion serving to facilitate registration between the projection and the slot. It will be observed that the projection may be inserted into said slot by merely pressing the door inwardly and longitudinally of the casing 2, and that the door will be prevented from rotating axially about the casing 2 by the fact that the stud 17 is positioned within 55 the slot 18.

To effect the registration of the projection and slot, that portion of the casing 2 diametrically opposite to the slot 18 is provided with a rectangular opening 19,

through which passes the hook shaped end 60 20 of a resilient fastening member 21. This member is principally arranged within the casing 2, and is mounted for sliding movement within a bearing 22 projecting from the inner surface of the casing. The end of 70 the member 21 is equipped with a pin 23 between which and the bearing 22 is interposed a coil spring 24, said spring normally tending to draw the hook shaped end 20 of the fastening member toward the inner edge 75 of the opening 19. Therefore, in assembling the lamp, the beaded rim 14 of the horizontal wall 12 of the door is initially placed in contact with that portion of the hooked end 20 of said fastening member which projects exteriorly of the casing 2. By this association of parts a fulcrum is provided for the lower portion of the door, and then by oscillating said door with the end 20 as a pivot, the stud 17 may be caused to enter 80 the slot 18. It will be observed, however, that the engagement of the panel or lens 15 upon the gasket 7 will cause said door to move outwardly thus placing the spring 24 under tension and serving to insure a close 85 contact between said lens and the gasket to insure the sealing of the reflector.

To lock the stud 17 within the slot 18 and to resiliently draw the door toward the casing 2, the interior of said casing, opposite 90 to the fastening member 21, is provided with a movable latching device 25. In this instance, the device 25 is in the form of a thin metallic plate and has its outer end equipped with a hook 27, which is movable toward or 100 away from the slot 18 so as to effect the opening or closing of the latter as regards the stud 17. The inner end of the device 25 is connected with an element 28 which is 105 slidably mounted within a fixed bearing 29 protruding inwardly from the casing 2. The inner end of the element 28 is provided with a pin 30 and between the bearing 29 and the pin 30 there is interposed a coil 110 spring 31 which normally tends to draw the latch device inwardly. The movements of the device 25 are controlled by providing the same with a manipulating knob 32, and located exteriorly of the casing 2, said knob being formed with a threaded extension 33 115 which operates in a bayonet slot 34 formed in the casing 2 and is threadedly received within an opening provided in the device 25. When the extension 33 of the knob is situated within the lateral branch 35 of the 120 bayonet slot the hook shaped end 27 of the latch device will be clear of the slot 18 so that the projection 17 may readily enter said slot. When this is accomplished the knob 32 is rotated laterally so that the extension 125 33 will be aligned with the longitudinally extending branch of the bayonet slot 34. When this alignment of parts is effected it

will be observed that the hooked ends 27 of the latch device will be brought into such position as to close the slot 18 so as to prevent withdrawal of the projection 17. However, the spring 31 is then free to act upon the device 25 so that the latter will be retracted by drawing the extension 33 longitudinally of the slot 34. This results in the engagement of the hook 27 with the stud 17 under the influence of the spring 31 so that the resilient pressure of the spring 31 will serve to draw the door 10 toward the casing 2 thus insuring a firm resilient engagement between the lens 15 and the gasket 7. To release the door from locked engagement with the casing 2, the above operation is simply reversed and this is brought about by simply forcing the knob 32 into the lateral branch 35 of the bayonet slot. The latch member may be securely retained in any of its adjusted positions by simply tightening the knob 32 down upon the casing 2 as it will be observed that the extension 33 of said knob has a threaded connection with the latch device 25. Also, the rear face of the hook 27 is provided with a curved depression 37, by means of which a close engagement between the hook 27 and the stud 17 is maintained. The slot 18 is of sufficient depth to prevent the stud or projection 17 from contacting with its end wall. By being thus proportioned the full resilient action of the springs 24 and 31 upon the door is brought about.

From the foregoing it will be gathered that the present invention comprehends a lamp wherein the door thereof may be quickly and positively connected in secured relationship with the casing 2 by a mere longitudinal insertion of the door upon said casing and that through the medium of the interlocking device described, it will not be necessary to rotate the door axially to effect its fastening, as is the case in the majority of lamps of the present construction. Through the provision of the manipulating knob 32 and its associated structure, convenient means are provided for locking the door in place, and the means are of such character as to permit these locking or unlocking operations to be performed with but a minimum of labor or exertion. Through the provision of the fastening member 21, the door is conveniently retained in position during the manipulations of the latch device 25 so that if necessary both of the operator's hands may be employed in the operation of said latch devices. Ordinarily, the latter is formed of such material as to preclude corrosion and thus the possibility of the device 25 rusting in engagement with the projection 17 is eliminated and the operation of the device thus rendered reliable even after long periods of disuse. Also,

the wall 12 of the door is extended so as to fully overlie the slot 18 and in this manner moisture is prevented from gaining access into the interior of the casing. In this connection it will also be observed that the latch device 25 is of such width as to at all times cover the bayonet slot 34, irrespective of the positions which said latch device may assume. This construction also has a tendency to eliminate moisture from the lamp. In view of the above it will be apparent that there is provided a structure whereby the objects of the invention have been achieved and that all of the advantageous features of construction and operation above pointed out are, among others, present. Essentially, the present invention provides means whereby the door may be connected with the casing with but a minimum of labor and effort, one which may be conveniently operated at all times and finally, in the provision of means whereby a firm sealing contact is maintained between the lens and the reflector gasket.

What I claim is:

1. In a vehicle lamp, a casing, an inwardly directed annular flange formed upon the rim of the casing, a reflector coöperative with the source of light carried by said casing, a flange formed upon the periphery of said reflector and arranged to seat directly upon said casing flange, a lens carrying door arranged to incase said casing and formed to include a ring shaped body having a beaded edge, means for holding said reflector and casing in locked relationship with said door, comprising a fixed projection carried by said door body and extending inwardly thereof in substantially parallel relation with said flanges, said casing being provided with a longitudinal slot to receive said projection upon inward longitudinal movement of said door, a latch member movably mounted within said casing and capable of blocking the entrance to said slot and to retain said projection therein, resilient means coöperative with said latch member and serving to exert a longitudinal pressure on said projection and to thereby draw said door into firm contact with said reflector and casing, a resilient hook member carried by said casing and disposed to engage with the beaded edge of said door to assist in drawing that portion of said door opposite to said projection toward said casing, and a manipulating element coöperative with said latch member and mounted exteriorly of said casing for permitting of the actuation of the latch member.
2. In a vehicle lamp, a casing, a reflector positioned within said casing, a door arranged to inclose said reflector and to hold the latter in secured relationship with said

casing, a rigid projection carried by said door and arranged to be slidably received within a slot formed in said casing, a latch device movably mounted within said casing and arranged to be projected across the mouth of said slot and into engagement with said projection so as to prevent the withdrawal of the latter from said slot, and re-

silient means coöperative with said device and serving when the latter is in locked relationship with said projection to exercise a pressure upon the latter so as to effect the retention of the door in resilient relationship with said reflector. 10

In testimony whereof I affix my signature. 15
JOHN W. BROWN.
